Inventor:

Hugh Woods,
By Marshall Daily, his

UNITED STATES PATENT OFFICE.

HUGH WOODS, OF CHICAGO, ILLINOIS, ASSIGNOR TO THE NATHAN MANUFACTURING COMPANY, OF NEW YORK, N. Y.

LUBRICATOR.

SPECIFICATION forming part of Letters Patent No. 645,026, dated March 6, 1900.

Application filed October 28, 1896. Serial No. 610,100. (No model.)

To all whom it may concern:

Be it known that I, HUGH WOODS, a citizen of the United States, and a resident of the city of Chicago, in the county of Cook and State 5 of Illinois, have invented a certain new and useful Improvement in Lubricators for the Valves and Cylinders of Locomotive-Engines, of which the following is a specification, reference being had to the accompanying drawing, 10 which represents in vertical section, partly in elevation, a lubricator embodying my invention in its preferred form.

The lubricator shown in the drawing in illustration of my invention is what is termed 15 a "double-feed" lubricator—that is to say, one in which both of the cylinders and valves of a locomotive-engine are lubricated from one common oil-reservoir. It will be understood, however, that the number of feed-out- 20 lets with which the lubricator is provided may be varied without departure from my invention.

I will first give a general description of the lubricator and will then more specifically describe those portions of the structure in which 25 my invention is found.

A is the oil-reservoir, and B the condenser, which at its top is provided with a union connection, to which is attached a pipe leading 30 to the boiler. The oil-reservoir is provided with the usual sight-glasses C and upper and lower sight-feed brackets D and D'. A pipe, which is not shown in the drawing, leads the water of condensation in the usual manner 35 from the condenser to the bottom of the oil-reservoir, and the pipe E leads the oil down to the channel F, which connects with the feed-nozzles G, the passage of the oil through which nozzles is regulated by the valves H in 40 the usual way.

K is a drain-valve.

L are valves to shut off steam from the glasses in case they should break, and M are equalizing-pipes.

45 The lubricator as thus far described is well known and requires no further description.

In ordinary lubricators of this class each of the upper sight-feed brackets contains, near the outlet-point into the oil-pipe which leads 50 to the cylinder, an outlet-nozzle with an exceedingly small opening, which nozzle, in con- nection with the equalizing-tubes M, serves in the usual manner to equalize the pressure within the lubricator. Owing to the fact that the steam-supply for the lubricator comes directly from the boiler, it is evident that the escape of steam and oil through the upper sight-brackets is practically continuous, even though the throttle-valve be closed and the engine motionless. It has been found, however, 55 that when the throttle-valve is opened and steam admitted to the steam-chest the small volume of steam passing through the nozzles condenses within the oil-pipes, resulting in a reduced pressure therein. This reduced pressure is not sufficient to resist the back pressure of steam from the steam-chest, with the result that the feed of the lubricator becomes irregular and eventually stops altogether. It is the object of my invention to overcome 60 this effect in a simple and reliable manner. To this end I combine with the lubricator and the oil or tallow pipe leading therefrom to the cylinder of the locomotive-engine, through which pipe there is a constant flow of steam and 65 oil in limited quantity to the cylinder through the usual plug or nozzle or its equivalent, a valve or piston plug, preferably of the differential type, controlling a steam-passage from the lubricator side of the apparatus to the 70 tallow-pipe and adapted to be operated by the back pressure from the cylinder to open said passage to the tallow-pipe under these conditions, and thus admit an additional supply of steam to neutralize the back pressure 75 from the cylinder. I prefer to so arrange things that, with the additional supply of steam, an additional supply of oil shall also be furnished at this time, the latter passing then not through the constantly-open choke- 80 plug alone, but also through the passage or 85 passages opened up by the valve. Thus not only is the back pressure from the cylinder neutralized or equalized by the additional volume of steam admitted at the lubricator 90 end of the oil or tallow pipe, but the oil-feed is increased also. In other words, the feed 95 is increased when the throttle is open and is decreased when the throttle is closed, because in the latter case the oil can pass through the 100 small constantly-open choke passage or plug only. These features, broadly considered, are

not new with me, as a lubricating apparatus embodying said characteristics is shown and described in United States Patent No. 267,430, granted to R. J. Hoffman on January 14, 1882.

5 In carrying out my invention I employ, in connection with a lubricator having suitable boiler, cylinder, and equalizing pipe connections, a piston-valve, or, as I have sometimes termed it, an "equalizing piston-plug," provided with a restricted constantly-open port or passage through it for a continuous supply of steam and oil in minimum quantity from the lubricator to the tallow-pipe and with additional ports or passages (distinct 15 and separate from the constantly-open minimum-supply port) which are open for the passage of an additional supply of steam or steam and oil only when the piston-valve is operated to move by the back pressure from 20 the cylinder. Thus the piston-valve, so far as its restricted constantly-open passage is concerned, corresponds in function to the choke-plug usually employed at the lubricator end of the tallow-pipe, while, so far as its 25 additional parts are concerned, it is a valve which controls said ports and opens them only when operated so to do by back pressure from the cylinder. The piston-valve is preferably of the differential type, having its 30 smaller area at the lubricator end and its larger area at its cylinder end, and I can and prefer to combine with it a spring which presses against it from its cylinder end, so as to nearly, but not quite, balance it against 35 the steam-pressure from the lubricator end, thus rendering it more sensitive to the back pressure from the cylinder.

I now proceed to a description of the structure embodying the foregoing features which 40 is shown in the drawing.

To each delivery end of the lubricator is attached a casing *a*, which is formed with a recess *c* and with openings *b*, leading to said recess from the delivery end of the lubricator. 45 It is also provided with a horizontal cylindrical bore or seat in which is mounted the piston-valve *d*, which is longitudinally movable in its seat. This piston-valve has in its lubricator end a longitudinal central opening *e* and in its periphery, beyond the lubricator end of the valve, a number of larger ports or 50 openings *f*. All of these openings *e* and *f* communicate with the large central passage *g* of the piston-valve. The piston-valve is of 55 the differential type, having its greater area at its cylinder end, and against this larger end bears a spiral spring *h'*, which is held and steadied in a cage *i*, consisting of the two rings *i'* *i''*, held together by longitudinal wires 60 or rods *i''*. This cage is contained in an enlarged portion of the bore of the casing *a*, and all of the parts contained in the casing are kept from falling out by the cap *k*, to the threaded neck of which is to be connected the 65 usual oil-pipe leading to the cylinder of the locomotive-engine. *m* is a hand-oiler by means of which the cylinder and valve may

be oiled on a downgrade in case the sight-feed becomes disabled, and *m'* is the passage from the hand-oiler opening into the casing at a 70 point beyond the cylinder end of the piston-valve.

The operation of my improved device is as follows: When the engine is standing still or running on a downgrade with no steam in 75 the cylinders, the steam passing continuously directly from the boiler through the equalizing-pipes *M* will press against the smaller head of piston *d*, compressing the spring *h'* and moving back the piston until the holes *f* 80 will be covered by the partition *n* of casing *a*. In this case only the very small hole *e* will be operative for the passage of steam and oil into the cylinder, and the lubricator will operate as an ordinary lubricator with fixed outlet-nozzle or choke-plug. When steam, however, is admitted into the cylinders, it will press against the larger head of piston *d* and, aided by the spring, overcome the pressure of steam against the small end of the piston, which latter will then assume the position shown in the drawing, with its holes *f* opening into the recess *c*. In this case, in addition to the small hole *e*, the holes *f* will be open to the passage of steam and oil, and the increased volume 95 of steam passing through these additional openings will effectually overcome the retarding effect of the back pressure from the cylinder.

I believe myself to be the first to have devised a lubricating apparatus provided with suitable cylinder and equalizing-pipe connections wherein the duct connecting the lubricator and the steam-chest at any point in the length of the duct is provided with a minimum-supply choked passage, a relatively-larger by-passage separate and distinct from the minimum-supply choked passage, and a valve for controlling said by-passage automatically operated by variations of pressure 105 within the duct.

What I claim, and desire to secure by Letters Patent, is as follows:

1. In a lubricating apparatus provided with suitable boiler, cylinder and equalizing pipe connections, and in combination with the lubricator and the steam chest or cylinder, a duct connecting the same containing a minimum-supply choked passage, a relatively-larger by-passage, separate and distinct from the minimum-supply choked passage, and a valve for controlling said by-passage automatically operated by variations in pressure 115 within the duct at the times and in the manner substantially as hereinbefore set forth.

2. In a lubricating apparatus provided with suitable boiler, cylinder and equalizing pipe connections, a casing communicating with the delivery end of the lubricator, provided with a choked or very small permanently-open passage for continuous flow of steam and oil in restricted quantity from the lubricator to the steam-chest, and with a valve-controlled by-passage separate and distinct from the mini-

imum-supply passage, for permitting an increased flow of steam and oil from the lubricator through the casing into the steam-chest, substantially as hereinbefore set forth.

- 5 3. In a lubricator having suitable boiler, cylinder and equalizing pipe connections, the combination with a valve-seat, of a differential valve longitudinally movable in said seat, having its larger area at its cylinder 10 end, and provided with a constantly-open restricted port for the passage of the minimum supply of oil and steam from the lubricator, and with additional ports, separate and distinct from the constantly-open minimum-supply port, opened only when the piston-valve 15 is operated by the back pressure from the cylinder, and communicating at this time with the lubricator, substantially as and for the purposes hereinbefore set forth.
- 20 4. In a locomotive-lubricator having suitable boiler, cylinder and equalizing pipe connections, the combination with the casing *a*, provided with one or more passages *b*, recess or cavity *c*, and partition *n*, of the piston *d* 25 seated and longitudinally movable in said casing, having the port *e* for a continuous current of steam and oil, and the additional ports

f for an intermittent current of steam and oil, substantially as and for the purposes hereinbefore set forth. 30

5. In a locomotive-lubricator, the combination of the casing *a* having recess *c* and passages therefrom to the lubricator, and partition *n*, the piston *d* seated and longitudinally movable in said casing and provided with 35 ports *e* and *f*, the spring *h* and its holder or cage *i* and the cap *k*, substantially as and for the purposes hereinbefore set forth.

6. In a locomotive-lubricator, the combination with the casing *a* and the piston *d*, seated and longitudinally movable in said casing and provided with ports *e* and *f* as described, of the hand-oiler mounted on the casing and communicating with the interior thereof at a point beyond the cylinder end of the piston 45 *d*, substantially as and for the purposes hereinbefore set forth. 40

In testimony whereof I have hereunto set my hand this 21st day of October, 1896.

HUGH WOODS.
